UNITED STATES PATENT OFFICE.

GEORGE W. GADD, OF INDIANAPOLIS, INDIANA.

COMBINED BLACKING-BOX HOLDER AND FOOT-REST.

SPECIFICATION forming part of Letters Patent No. 269,192, dated December 19, 1882.
Application filed March 23, 1882. (No model.)

To all whom it may concern:

Be it known that I, GEORGE W. GADD, of the city of Indianapolis, county of Marion, and State of Indiana, have invented certain new and useful Improvements in Combined Blacking-Box Holder and Foot-Rest, of which the following is a specification.

The object of my said invention is to produce a combined blacking-box holder and foot-rest in which said holder and the box of blacking held thereby shall be retained beneath said foot-rest when not in use, but wherein the pressure of the foot of the user when placed upon said rest shall operate to throw said holder and blacking sidewise from beneath said foot-rest. The object is accomplished by mounting said box-holder on an arm, pivoting said arm to the under side of said foot-rest, and attaching a lever to said foot-rest which shall rest against said arm at one end and project up so as to be pressed against by the foot of the user, and thus operated to force said arm and box-holder out where the blacking can be reached for use.

Referring to the accompanying drawings, which are made a part hereof, and on which similar letters of reference indicate similar parts, Figure 1 is a top or plan view of my improved device, the box-holder being forced out as when in use; Fig. 2, an under side plan of the same, the box-holder being in its ordinary position, the position illustrated by Fig. 1 being shown by dotted lines; Fig. 3, a side elevation of the same; and Fig. 4 a transverse vertical sectional view as seen when looking to the left from the dotted line *xx*.

In said drawings, the portions marked A represent the frame-work or foot-rest proper of my invention; A', a cross-bar thereon for sustaining the swinging arm; B, the swinging arm carrying the blacking-box holder; C, said blacking-box holder; D in Fig. 3, a blacking-box in said holder; E, a spring whereby the arm B, holder C, and the blacking-box are held beneath the foot-rest, as shown in Figs. 2, 3, and 4, when not forced therefrom; and F, a lever by which the foot of the operator is enabled to throw said parts out in the position shown by Fig. 1, where the blacking can be reached for use.

The operation of my invention is as follows:

A box of blacking, D, is secured in the holder C by means of a clamp, *c*, and clamp-screw *c'*, or otherwise. The holder through its arm B is secured to the frame-work A by the pivot *b*, and swings laterally thereon, being also sustained by the bar or guide A'. The spring E holds said arm, holder, and box in the position shown by Fig. 2 until a sufficient force is applied to overcome that of the spring. When it is desired to use the device the heel of the user presses down the lever F, (which is pivoted to the frame-work A by the pivot *f*), throwing the arm and holder around into the positions shown in Fig. 1, rendering the blacking in the box accessible. When the foot is removed and the pressure on the lever F thus relieved the force of the spring automatically draws the holder, &c., back to the former position. Thus the blacking is brought into a position where it is accessible for use, and returned to its covered position, without any necessity of touching it or its holder with the hand, and a frequent cause of soiling the hands is thus avoided.

Having thus fully described my said invention, what I claim as new, and desire to secure by Letters Patent, is—

1. The combination, with a foot-rest, of a blacking-box holder secured thereto by a pivot, on which it is adapted to move laterally, a spring adapted to hold said holder in position beneath said rest until forced out, and means whereby the pressure of the foot of the user will force said holder from beneath said rest, substantially as set forth.

2. The combination of the rest A, holder B C, spring E, and lever F, substantially as set forth.

3. A combined blacking-box holder and foot-rest wherein the holder is pivoted beneath the rest, and is adapted, by means substantially as specified, to be forced laterally from its position by the pressure of the foot of the user, substantially as set forth.

In witness whereof I have hereunto set my hand and seal, at Indianapolis, Indiana, this 25th day of March, A. D. 1882.

GEO. W. GADD. [L. S.]

In presence of—

C. BRADFORD,
CHAS. L. THURBER.
